UNITED STATES PATENT OFFICE.

ERNEST D. FIEUX, OF NEW YORK, N. Y., AND HARRY S. WHEELER, OF RAHWAY, NEW JERSEY, ASSIGNORS TO L. J. WING MANUFACTURING COMPANY, A CORPORATION OF NEW YORK.

AIR-PROPELLER.

1,304,671.

Specification of Letters Patent. Patented May 27, 1919.

Application filed September 2, 1914. Serial No. 859,743.

To all whom it may concern:

Be it known that we, ERNEST D. FIEUX and HARRY S. WHEELER, citizens of the United States, and residents, respectively, of New York city, county and State of New York, and Rahway, in the county of Union and State of New Jersey, have invented certain new and useful Improvements in Air-Propellers, of which the following is a specification.

10 The invention relates to air propellers preferably of the fan blower type wherein the air is propelled parallel with the axis of the blower.

15 Air propellers of this character have been previously constructed with a rotatable fan surrounded by a casing having its inner wall in close proximity with the end of the fan blades. In this construction, as the fan re- 20 volves, a portion of the air which is drawn in by suction is expelled radially from the periphery of the fan by centrifugal force, and since the ends of the fan blades are in close relation with the casing, there is no

25 space therebetween in which this air may escape and it consequently becomes compressed against the inner wall of the casing and then seeks its way out from between the blades on both sides of the fan. It has

30 been found by experiment that a large portion of this radially forced air seeks its way out back through the suction opening, thus a material percentage of the air drawn in by the fan is lost and not propelled 35 through the apparatus; and, further, that this radially expelled air by being compressed against the inner wall of the casing offers a resistance to the rotation of the fan and chokes the suction opening.

40 The object of this invention is to overcome the above deficiency and to increase the efficiency of air propellers.

To this end the invention consists of an air propelling device comprising a casing 45 having an opening with a rotatable blower having vanes in the plane of said opening creating a current of air composed of several components, one a main stream and another a stray stream tending to exert a 50 choking effect between the vanes and the walls of the opening, and means for relieving the choking effect of the stray stream and for directing it into substantially the same path as the main stream. The invention further consists in an air propelling

device which comprises a rotatable blower having vanes creating a current of air having several components angularly related to each other, and means for directing both of said components into the same path. 60

In the accompanying drawings the invention is described in a concrete and preferred form but changes of construction may be made without departing from the legitimate and intended scope of the invention as expressed in the appended claims. 65

In the said drawings:

Figure 1 is a vertical sectional view of a preferred form embodying the invention.

Fig. 2 is a front view of a casing as shown 70 in Fig. 1 with the fan removed therefrom.

Fig. 3 is a detail view taken on line 3—3 of Fig. 2 showing the connection of the fan supporting means with the casing.

Fig. 4 shows a modification of the de- 75 flector at the suction end of the casing.

Like reference characters indicate similar parts throughout the drawings and specification.

1 indicates a cylindrical casing having its 80 opposite ends open and which is shown as being fitted or made into a wall 2 but which may be supported by any suitable supporting means.

An annular flange 3 is extended from the 85 inner wall of the casing at a point adjacent one end thereof and is directed forwardly and inwardly toward said end. In the embodiments shown herein it is preferred to gradually curve said flange inwardly so as 90 to provide the concave deflecting surfaces 3^a for a purpose which will be presently set forth.

A rotatable shaft 4 is extended into the casing 1 and is supported by the stud bolts 95 5 in a manner which has been set forth in detail in a copending application. The flange 3 is solid to the edge of the casing at points where the stud bolts 5 are to be supported and are suitably threaded to receive 100 the threaded end of the bolts as best seen in Fig. 3. Mounted on the extended end of the shaft 4 to rotate therewith is an air blower 6, of any usual construction, and is disposed in the plane of the annular flange 105 3 so as to rotate within the same with the rear outer portions of the blades thereof in approximate close relation with the innermost end of the flange 3.

It will be apparent from the construction 110

above set forth that a space is provided between the rotary path of the blower and the casing which is to receive the air radially expelled from the axis of the blower by centrifugal force and which will deflect or direct the path of the same in parallelism with the path of the air forced axially from the blower. To prevent the air centrifugally forced by the blower from escaping 5 from the blades thereof back through the suction opening 7 of the casing before it reaches the space between the blower and the casing, an annular ring 8 is mounted in any suitable way to the edge of the suction 10 end of the casing 1. This ring 8 is of approximately the same diameter as the casing but has the diameter of its central opening of a lesser diameter than the diameter of the blower so as to restrict the 15 admission of air to the fan and to prevent any outward flow of radially expelled air from the ends of the fan through the suction opening.

The ring 8 is preferably removably held 20 in position by the sleeve members which surround the stud bolts 5, and which bear against the ring and force the same in juxtaposition with the edge of the casing 1 and the flange 3 as the bolts are threaded 25 therein. Thus it will be seen that this ring may be easily removed so that the blower 6 may be withdrawn from the casing for any desired purpose.

It will be noted that by the present invention provision has been made so that the air radially forced from the blower by centrifugal force will not in any way impede the rotary operation of the fan or choke the suction opening so as to prevent the efficient 30 operation thereof, and that this centrifugally forced air is collected and deflected to a desired path. It is to be understood that the exact and specific construction of the deflector or flange 3 may be varied 35 as desired, to any different formation or angle that falls within the scope of the appended claims.

What is claimed, is:

1. An air propelling device, comprising a rotatable blower having vanes creating a current of air comprising a main stream having a generally axial direction and stray streams having generally radial directions, a casing for said blower comprising a portion closely surrounding the peripheral edges 55 of said vanes at the inlet side, a portion of greater diameter in advance of said first mentioned portion and an intermediate connecting portion having a curved surface surrounding the peripheral edges of said 60 vanes and diverging therefrom in a direction toward the delivery side of said blower, said connecting portion having its surface shaped to deflect the air discharged from the ends of said vanes into a generally axial direction in parallelism with the main stream.

2. An air propelling device, comprising a rotatable blower having vanes creating a current of air comprising a main stream 70 having a generally axial direction and stray streams having generally radial directions, a casing for said blower comprising two cylindrical portions concentric with the axis of rotation of the blower, one such portion 75 closely surrounding the peripheral edges of the blower vanes at their inlet side, the other portion being of a larger diameter and surrounding said blower vanes at their delivery side and in advance thereof, and an intermediate portion connecting said two cylindrical portions and having its surface shaped to deflect said stray streams to a generally axial direction in parallelism with the main stream.

Signed at New York city, in the county of Westchester and State of New York, this 25th day of April A. D. 1914.

ERNEST D. FIEUX.
HARRY S. WHEELER.
